(57) **CLAIM**

The ornamental design for a running computer, as shown and described.

DESCRIPTION

FIG. 1 is a perspective top view of a running computer showing my new design;

FIG. 2 is a perspective bottom view thereof;

FIG. 3 is a top view thereof;

FIG. 4 is a bottom view thereof;

FIG. 5 is a front side view thereof;

FIG. 6 is a back side view thereof;

FIG. 7 is a right side view thereof; and,

FIG. 8 is a left side view thereof.
